UNITED STATES PATENT OFFICE.

THOMAS McAVITY STEWART, OF MONTREAL, QUEBEC, CANADA.

VALVE.

1,132,886.

Specification of Letters Patent. Patented Mar. 23, 1915.

Application filed June 23, 1911. Serial No. 634,936.

To all whom it may concern:

Be it known that I, THOMAS McAVITY STEWART, of the city of Montreal, in the Province of Quebec, Canada, have invented 5 certain new and useful Improvements in Valves; and I do hereby declare that the following is a full, clear, and exact description of the same.

This invention relates more particularly 10 to valves of the type in which a pilot or auxiliary valve is first manually operated and the main valve then operates automatically through the action of an overbalancing member, valves constructed according to this invention being especially adapted for use in 15 connection with steam whistles or the like.

The invention has for its object to provide 20 a valve which will be positive in its action and generally to improve the construction of valves of this type.

The invention may be said to consist of the construction, arrangement and combination 25 of parts as hereinafter described and set forth in the claim.

For full comprehension however of my invention reference will be had to the accompanying drawings forming a part of this specification, in which similar reference characters indicate the same parts and 30 wherein:

Figure 1 is a sectional view of a valve constructed according to my invention. Fig. 2 is a detail sectional view of the valve proper taken at right angles to Fig. 1 on the line 35 2—2 Fig. 1.

The valve casing is shown at 1 and is provided at one side with an intake port 2 adapted to be connected to a source of pressure fluid supply and at its opposite side 40 with an outlet opening 3 here shown as communicating with a steam whistle a portion of which is indicated at 4.

Extending between opposite walls of the valve casing and separating the intake and 45 outlet parts from one another is a partition 5 having a tapped opening 6 in which is screwed a short sleeve 7 constituting the valve seat upon which the main valve 8 seats. The valve 8 is provided with a forwardly extending hollow stem which may 50 comprise an interior hollow member 9 integral with the valve and a sleeve 9¹ placed over the said member 9 and having a piston 10 formed integrally upon the forward end 55 thereof, this sleeve 9¹ being of smaller diameter than the interior of the seat sleeve 7 to

permit of passage of fluid when the valve 8 is lifted and having a series of outwardly projecting ribs 9^a whereby it is guided in the said seat sleeve. The piston 10 extends into a short cylinder 11 the annular wall whereof forms an integral part of the valve casing while its forward end is closed by a cap or plug 12. The combined length of the sleeve 9¹ and piston 10 is less than the distance between the underside of the valve 8 and the inner end of the piston cylinder 11 formed by the plug 12. This piston 10 is of larger area than that of the valve 8 so that when fluid under pressure is admitted to the space 60 between the piston and cap 12 the pressure on the piston will overbalance the pressure on the valve and cause the latter to open. The extent to which the valve opens may be regulated by means of a screw 13 threaded 65 into a plug 13¹ screwed into a tapped opening in the valve casing and having at its forward end a disk 13^a having forward projections 13^b against which a plug 13^d carried by the valve, and to which further reference 70 will be made, bears when the valve opens, a lock nut 13^e being screwed on the end of the screw 13. A wearing ring 14 of brass or the like is mounted in an annular groove in the 75 outside of the piston.

The admission of pressure fluid to the space in front of piston 10 is controlled by a pilot valve 15 located within the hollow stem 9 and seating in a seat 16 formed by a contraction of the passage therethrough, the 80 valve having a forwardly projecting stem 17 which extends through the piston 10, cap 12 and a sleeve 18 threaded into a tapped opening 19 in the latter, to a point outside the valve casing and in close proximity to the 85 lever 20 pivoted as at 21 to the valve casing and provided with any suitable connection whereby it may be manually operated. The rear end of the valve 15 extends to a point a short distance from a plug 13^d screwed into 90 a tapped opening in the front end of the main valve and having a longitudinal passage 22 for the admission of fluid to the space, the fluid passing thence through an axial passage 23 and transverse passages 24 95 in valve 15 to an annular space 25 between the valve 15 and the interior wall of the stem 9 in front of the valve seat 16 and thence, upon valve 15 being lifted through the annular space 26 between the valve stem 17 and 100 the interior wall of the contracted portion 105 of the passage through the hollow stem 9.

A spring 30, surrounding the stem 17 and bearing at opposite ends between the cap 12 and a pin 31 extending transversely through the stem, returns the valve 15 to its seat 5 when the lever 20 is released.

Operation: To open the valve, lever 20 is depressed and the valve 15 is lifted through the medium of stem 17, from its seat. The pressure fluid then passes through passages 10 22, 23, 24, 25, 26, to the cylinder 11. The pressure upon piston 10 overbalances the pressure on valve 8 and the latter opens. When lever 20 is released the spring 30 closes the valve 15 when the slight leakage 15 between the stem 17 and parts 11 (no packing being provided between these parts) and 18 allows the fluid to exhaust from the cylinder 11 and the valve 8 closes.

I claim—

20 In a valve, the combination with a casing having an inlet and an outlet communicating with each other, a partition located between the inlet and outlet and having an opening therein, a main valve seat within 25 said opening and a piston cylinder formed in the casing, of a main valve adapted to be seated upon the main valve seat and having a tapped opening therein, a bored plug screwed into the opening in the main valve, 30 an adjustable stop for limiting the opening movement of the main valve, such valve comprising a hollow stem communicating

with the opening in the valve and leading to the piston cylinder, an auxiliary valve seat formed in said hollow stem, a sleeve 35 slidably mounted upon the stem, engaging at one end with the underside of the main valve and having a piston head at its opposite end and located in and spaced from the inner end of said piston cylinder, such 40 sleeve being of smaller diameter than the interior of the main valve seat and having outwardly projecting ribs thereon, a closely fitting auxiliary valve located in said hollow stem between the auxiliary valve seat and 45 the bored plug, such auxiliary valve being reduced in diameter at a point above its seat and having a longitudinal passage therethrough and ports leading from such passage to the exterior of the reduced portion of the valve, a loose fitting valve stem extending from the auxiliary valve to the exterior of the casing, a spring yieldingly holding the auxiliary valve upon its seat and means for opening the auxiliary valve 50 against the influence of the spring.

In testimony whereof, I have signed my name to this specification, in the presence of two subscribing witnesses.

THOMAS McAVITY STEWART.
